ELECTRIC COMPANY, A CORPORATION OF NEW YORK.

SPARK PLUG.

1,403,501.

Specification of Letters Patent. Patented Jan. 17, 1922.

Application filed October 18, 1917. Serial No. 197,206.

To all whom it may concern:

Be it known that I, LEONARD KEBLER, a citizen of the United States, residing at Bronxville, in the county of Westchester 5 and State of New York, have invented certain new and useful Improvements in Spark Plugs, of which the following is a specification.

The principal object of my invention is 10 to provide a new and improved spark plug for use with gas engines. Other objects of my invention relate to providing a spark plug that shall be non-leaking under high compression, that shall maintain its integrity 15 under any extremes of temperature and under sudden changes of temperature to which it may be subjected in practice, that shall be effectively insulated for all 20 temperatures of use, and shall otherwise be efficient and durable. All these and other 25 objects of my invention will be more readily appreciated in connection with the following specification and claims taken with the accompanying drawings.

Ordinary automobile engines are operated 30 at a compression (before ignition) of not much, if any, more than 60 pounds per square inch, but the modern aeroplane engine is operated at a much higher compression, namely, about 125 pounds. With this 35 much higher compression and the accompanying higher temperatures and abrupt and extreme temperature changes, serious troubles are encountered if the ordinary 40 spark plugs such as used with automobile engines are employed. The porcelain sleeve ordinarily used in automobile spark plugs has a coefficient of heat expansion per degree centigrade between 0.0000030 and 45 0.0000060, whereas the coefficient of expansion of iron is about 0.0000120. Hence, even though the parts may be initially assembled tightly, they are likely to get loose and permit leakage at the extremely high temperatures 50 at which aeroplane engines are operated. In my improved plug such leakage is impossible, because in my plug the shell and insulator are sealed with an enamel which is most intimately united to the iron, 55 and to the insulator, thus completely sealing the plug against leakage. This enamel is selected and prepared to have an elastic range sufficient for any differential expansion between the insulator and the iron.

55 The electrical resistivity of porcelain,

glass, and substances of that character usually falls off very decidedly with increasing temperatures, so that in an ordinary spark plug with a porcelain bushing between the electrode and the iron shell, if the hot cylinder gases come in contact therewith, then the electric current impulses will leak right through the porcelain between the electrode and the shell when such a plug is attempted to be operated at the high temperature 60 encountered in aeroplane practice. Illustrating the failure in resistivity at higher temperatures, I will mention that for temperatures centigrade and for resistivity expressed in megohms, ordinary soda lime 70 glass is 500,000 at 18° and is only 100 at 145°; Jena tubing is 200,000,000 at 18°, 36,000,000 at 115°, 18,000,000 at 150° and 0.01 at 750°.

Mica is a very superior insulator and preserves this quality at high temperatures and therefore I also provide mica insulation to prevent any leakage of current, where the heat is intense. However, mica disintegrates when exposed directly to the hot 80 engine gases and it must be carefully protected from them.

The parts of a spark plug with which the hot engine gases come in contact are liable to be subjected to abrupt and extreme temperature changes, as when after driving at full speed, the engine is shut off and air is drawn through the cylinders. Under these circumstances, such a member as a thick piece of porcelain would crack on its face, 90 because, having a considerable coefficient of heat expansion as already mentioned, the surface would contract and crack before the interior portion could contract. As a protective barrier I employ a comparatively 95 thin shell, so that its temperature condition will change more nearly at once throughout and it will not be subjected to extreme strains on account of differential heating and cooling. A satisfactory material for 100 this shell is porcelain, glass, or fused silica, or lava, or similar material. By having the shell member thin-walled, any dangerous differential expansion of its parts is avoided, as heretofore explained.

105 The coefficient of heat expansion of fused silica is very low, namely, only about 0.0000006, and this is an important quality to give permanence with respect to sudden temperature changes, because it reduces the 110

degree of differential expansion and contraction. As is well known, fused silica is also highly refractory to heat and in addition it has a high resistivity which it preserves in high degree when its temperature is raised. With the same units as above, it is over 200,000,000 at 18° to 150°, 2,500,000 at 250°, 30,000 at 350°, and 30 at 700°. Thus, it will be seen that fused silica is a satisfactory material for the barrier. It is difficult to obtain fused silica in massive shapes, such for example as the porcelain members of ordinary automobile spark plugs, but it is commonly found in chemical laboratories drawn out in tubes or in the form of crucibles or evaporating dishes. I sometimes employ a simple shape of fused silica which is easy to make.

By making the plug electrode of large size, it functions as a conductor of heat and so relieves the mica surrounding it from becoming overheated.

In the drawings I have illustrated two specific forms in which my invention may be embodied, but it will be understood that these are by way of example and that my invention comprehends other modifications. Proceeding now to a specific description of the forms shown in the drawings,

Fig. 1 shows an axial section of one modification and Fig. 2 shows a similar view of another modification.

In Fig. 1 the main iron shell 11 is screw threaded at 12 to engage the usual hole in the cylinder head. The thin-walled cup 13 of porcelain or fused silica or other material has its flange lying against a washer 14 of compressible or deformable material. This washer 14 absorbs any strains that might otherwise break the cup 13. The large copper electrode 15 extends through a central hole in the bottom of the shell 13, the flange 16 abutting against the bottom of the shell around the hole. The nickel electrode terminal 17 is securely engaged in the electrode 15. Thin sheets of mica are wrapped round and round the electrode 15 at 18. The insulator 27 is then put in place. After the parts are assembled to the extent heretofore described, the shell 11 and the insulator 27 are cemented together with a fused vitreous enamel 19 having (when cooled) approximately the same coefficient of heat expansion as the iron, or having an elastic range which allows the enamel to adhere to the shell 11 and to the insulator 27 in spite of any difference in expansion when heated. This is accomplished by heating the previously assembled parts to proper temperature, a clear red heat, and then introducing the enamel in powdered or granular form and continuing the heating until the enamel is fused. The electrode 15 and the insulator 27 are then cemented in the same way at 20. Then the parts are cooled and the enamel sets,

tightly engaging the interior wall of the shell 11 at 25 and around the insulator 27 at 24 and also likewise engaging the electrode 15 and the insulator 27. Thereafter the nuts 22 and 23 are mounted on the screw threaded portion 21 of the electrode 15 so that a conductor can be engaged thereto.

The terminal 26 of nickel is secured in a hole in the lower edge of the plug shell 11.

I prefer to form the insulating member 18 by wrapping the mica sheets around cylindrically, instead of building up washers, because for example, if the member 18 is constructed in the latter manner, any trace of iron in one washer gives a radial path of comparatively low resistance through the member; whereas by my manner of formation, any flaw in one sheet of mica will be comparatively insignificant as it will not register with similar flaws in other layers.

Referring to Fig. 2, this is the same as Fig. 1; except that the shell 13 is a cylinder without constriction at its lower end.

Thus it will be seen that I have provided a spark plug which has the desirable quality of gas tightness when operated at high compression, which is effectively insulated even when operated at a very high temperature, and which moreover, is very durable and rugged at high temperatures and when subjected to abrupt temperature changes.

I claim:

1. A spark plug comprising a metal shell, an axial electrode therethrough, mica insulation around the electrode within the shell, an insulating element around said mica insulation, insulating material around said element and within the shell and engaged by fusion with the inside shell wall and said element, and a protective insulating barrier around the electrode exposed within the shell.

2. A spark plug comprising a metal shell, an axial electrode therethrough, mica insulation around the electrode within the shell, an insulating element around said mica insulation, insulating material around said element and within the shell and engaged by fusion with the inside shell wall and said element, and a protective insulating thin walled barrier around said electrode and a portion of said mica insulation exposed within the shell.

3. A spark plug comprising a metal shell, an axial electrode therethrough, insulating material of high resistivity within said shell around said electrode, said electrode having a terminal projecting beyond said insulating material, a barrier exposed within the interior of the shell between said insulating material and the electrode terminal, and insulating means filling the space within the metal shell around the first mentioned insulating material and the electrode and comprising enamel intimately engaging the in-

side wall of the shell and the electrode by fusion therewith, said enamel having its coefficient of heat expansion near enough to that of the iron to permit differential expansion at operating temperatures without exceeding the elastic range.

4. A spark plug comprising a metal shell with an interior circumferential ledge, an axial electrode, a washer resting on said

ledge around the electrode, a thin walled cup of material of permanent character with respect to heat and abrupt temperature changes lying against said washer, said cup having a hole in the bottom with the electrode projecting therethrough and insulating material within the shell around the electrode and behind said cup as a barrier.

LEONARD KEBLER.
